ATTORNEY

UNITED STATES PATENT OFFICE.

JOHN Q. A. WALKER, OF NEW YORK, N. Y.

DESIGN FOR A BOTTLE-DISPLAY STAND.

SPECIFICATION forming part of Design No. 30,331, dated March 14, 1899.

Application filed January 30, 1899. Serial No. 703,947. Term of patent 3½ years.

To all whom it may concern:

Be it known that I, JOHN Q. A. WALKER, residing at New York, in the county of New York and State of New York, have invented 5 a new and useful Design for a Bottle-Display Stand, of which the following is a specification, reference being made to the accompanying drawing, forming part thereof.

My design for a bottle-display stand is illustrated by a view in perspective.

As shown in the drawing, the leading or essential features are as follows: A frame A, providing inclined supports B and lower terminal rests C for the bottles, and concave

bottle-carriers D and E, fixed to the supports and arranged in series either or both horizontally or vertically, according to the number of bottles to be presented to view.

Having thus described my invention, what I claim is—

The design for a bottle-display stand, as herein shown and described.

In testimony whereof I affix my signature in the presence of two witnesses.

JOHN Q. A. WALKER.

Witnesses:

B. S. BETTMAN,
INGERSOLL LOCKWOOD.
